HYDROCARBON CONVERSION

Hillis O. Folkins, Skokie, and Carlisle M. Thacker, Highland Park, Ill., assignors to The Pure Oil Company, Chicago, Ill., a corporation of Ohio

No Drawing. Application December 3, 1943,
Serial No. 512,780

3 Claims. (Cl. 196—52)

1

This invention relates to conversion of hydrocarbons and more particularly to the cracking of hydrocarbons containing three or more carbon atoms per molecule to hydrocarbons of lower boiling point.

In our application Serial No. 494,249, filed July 10, 1943, we have disclosed and claimed the process of cracking hydrocarbons in the presence of small amounts of organic compounds containing a bromine substituted aliphatic hydrocarbon group. In addition to the specific compounds therein disclosed, compounds such as benzyl bromide, in which bromine is substituted for hydrogen in an alkyl radical linked to an aromatic nucleus, fall within the broad class of compounds covered by the claims of that application.

We have now discovered that bromine substituted cyclic compounds in which bromine is attached to one carbon in the cyclic nucleus, regardless of the presence or absence of bromine in an alkyl side chain, are also very effective in accelerating the decomposition of hydrocarbons when used in the amounts and under the conditions set forth in the aforesaid application.

Halogenated cyclic hydrocarbons which contain at least one bromine atom substituted in the ring such as brominated benzenes, brominated toluenes, brominated xylenes, brominated naphthalenes, brominated anthracenes, bromochlorobenzenes, bromofluorobenzenes, bromoiodobenzenes are particularly useful.

Examples of bromine-substituted cyclic compounds which are useful as sensitizers in our process are:

Bromobenzene
1-bromo-3-chlorobenzene
1-bromo-4-chlorobenzene
1-bromo-4-fluorobenzene
1-bromo-2-iodobenzene
1-bromo-3-iodobenzene
1-bromo-4-iodobenzene
1,2-dibromobenzene
1,3-dibromobenzene
1,4-dibromobenzene
1,2,3-tribromobenzene
1,2,4-tribromobenzene
1,3,5-tribromobenzene
1,2,4,5-tetrabromobenzene
1,2,3,5-tetrabromobenzene
Pentabromobenzene
Hexabromobenzene
Bromotoluene (o, m and p)
4-bromo-o-xylene
4-bromo-m-xylene
2-bromo-p-xylene

2

4,6-dibromo-m-xylene
1-bromonaphthalene
2-bromonaphthalene
9-10-dibromoanthracene
5 o-Bromo anisole
p-Bromo anisole
1-bromo-2-nitrobenzene
1-bromo-3-nitrobenzene
1-bromo-4-nitrobenzene
10 2,4,6-tribromophenol
Bromocyclohexane
1,2,3,4,5,6-hexabromocyclohexane
Bromocyclopentane

15 Compounds containing more than one bromine atom in the ring are preferred over corresponding compounds which have only one bromine atom attached to a carbon atom of the cyclic nucleus.

20 The sensitizer may be added to the charging stock before charging it to the heating and conversion zones, or it may be injected directly into the conversion zone. Brominated cyclic compounds are effective as cracking accelerators or sensitizers in amounts as low as .1% by weight of the charging stock. Amounts between .1 and 5% by weight may be used effectively, although larger amounts are useful. We prefer not to use amounts in excess of 3% by weight since amounts below 3% provide satisfactory acceleration of the cracking reaction without causing the presence of objectionable amounts of brominated compounds in the resulting product. Our experiments indicate that amounts of sensitizer, particularly where the sensitizer is a brominated benzene ring compound, of 1% or less by weight will generally give satisfactory results.

25 Sensitizers in accordance with our invention are useful in conventional thermal cracking processes at either atmospheric, sub-atmospheric or super-atmospheric pressure. Cracking of hydrocarbon oils and gases may be carried out with brominated aromatics within the temperature range of approximately 650° F. to 2000° F., depending on the nature of the charging stock and the type of product desired. Where cracking of hydrocarbon oils to gasoline is practiced, the temperature may range from approximately 650 to 1200° F. When cracking gases or oils are 30 cracked to aromatics, temperatures of approximately 1000° to 1500° F. may be resorted to. When it is desired to crack hydrocarbon oils or gases to butadiene, temperatures of the order of 1300 to 1600° F. may be used. Where cracking 35 of oils or gases to lower molecular weight gaseous

hydrocarbons is practiced, temperatures of 1500 to 2000° F. may be used.

In carrying out our invention we prefer to use bromine compounds which are volatile at the reaction temperatures. Where compounds which are unstable at elevated temperatures are used, it may be desirable to inject the sensitizer directly into the reaction zone in order to prevent decomposition thereof before the charging stock reaches cracking temperatures. Brominated polycyclic aromatics may be used as well as the brominated monocyclic compounds.

In order to demonstrate the effectiveness of the brominated aromatic compounds, in which bromine is linked to carbon in an aromatic ring, as cracking sensitizers, Pennsylvania gas oil was mixed with 0.5% by weight of p-dibromobenzene and cracked in a laboratory tube and drum cracking apparatus at temperatures of approximately 887° F. and 500 pounds per square inch pressure. The results obtained on the run using the p-dibromobenzene were compared with results obtained on similar runs, without any sensitizer and with p-dichlorobenzene. The results on three runs are given in the following table.

10

20

25

octane number to that produced without sensitizer.

Although our invention is applicable to all known types of hydrocarbon cracking processes, both catalytic and purely thermal, it is particularly adapted for use in connection with purely thermal operations in which no solid catalyst is used. Our invention may be used in present types of thermal cracking processes without modifying such processes or the apparatus in which they are conducted, except to the extent necessary to provide for the addition of the sensitizer to the charging stock at some point in the operation prior to the time the products leave the reaction zone.

It is to be understood that our invention is directed to the use of nuclear brominated isocyclic compounds generally, regardless whether groups or elements other than bromine are attached to the ring.

It is claimed:

1. Process for cracking hydrocarbons which comprises subjecting said hydrocarbons in the absence of solid catalysts to suitable cracking conditions of time, temperature and pressure in the

Table

Run No.	Sensitizer	Per cent of sensitizer by wt. of charge	Rate in gal./hr. of charging stock and gas oil from Pa. crude + sensitizer	Temp., ° F.	Pressure per sq. inch	Volume per cent yield 100° F. I. B. P., 400° F. E. P. gasoline based on charge	Octane No. of gasoline	Gas yield per gal. of charge		Total gas analysis, mole per cent	
								C ₃ and lighter	C ₄ and heavier	Unsaturates	H ₂
644			1.005	887	500	17.5	56.8	1.96 cu. ft., 69.97 g.	0.35 cu. ft., 30.23 g.	22.9	5.1
649	p-Dibromo benzene	0.50	0.991	887	500	22.8	58.3	2.12 cu. ft., 72.23 g.	0.38 cu. ft., 32.87 g.	19.8	8.5
650	p-Dichloro benzene	0.50	0.994	887	500	17.3	49.3	1.94 cu. ft., 69.39 g.	0.37 cu. ft., 29.83 g.	22.8	5.3

In each run the charging stock after admixture with the sensitizer, except in run 644 in which no sensitizer was used, was preheated in the heating coil to the desired reaction temperature and then charged to the reaction chamber, after which the reaction products were cooled and separated into liquid and gas fractions for analysis.

It will be seen from the table that the gasoline yield in run 649 using p-dibromobenzene as sensitizer was approximately 30% greater than the yield in run 644 using no sensitizer, and that the octane number of the gasoline produced in run 649 was somewhat higher than that produced in run 644. P-dichlorobenzene on the other hand was not only ineffective in accelerating the rate of reaction, but produce a gasoline with inferior

presence of a small quantity of p-dibromobenzene.

2. Process for cracking hydrocarbons containing 3 or more carbon atoms in the molecule to hydrocarbons containing less carbon atoms in the molecule which comprises subjecting said hydrocarbons to suitable conditions of time, temperature and pressure in the presence of a small amount of p-dibromo-benzene.

3. The process of cracking hydrocarbon oil to gasoline boiling hydrocarbons which comprises subjecting said oil in the absence of solid catalysts to temperatures of approximately 650° to 1400° F. in the presence of from approximately 0.1 to 5% by weight of p-dibromo-benzene.
